US00D880314S

(12) **United States Design Patent** (10) Patent No.: **US D880,314 S**
(45) Date of Patent: ** Apr. 7, 2020

(54) **TORTILLA PACKAGING CONTAINER**

(71) Applicant: **General Mills, Inc.**, Minneapolis, MN (US)

(72) Inventor: **David Galavis**, La Rioja (ES)

(73) Assignee: **General Mills, Inc.**, Minneapolis, MN (US)

(**) Term: **15 Years**

(21) Appl. No.: **29/648,117**

(22) Filed: **May 18, 2018**

(51) LOC (12) Cl. **09-03**

(52) U.S. Cl. **D9/761**
